CLAIM

We claim the ornamental design for a “capotasto and tuner assembly,” as shown.

DESCRIPTION

FIG. 1 is a perspective view of a capotasto and tuner assembly;

FIG. 2 is a right-side view of the capotasto and tuner assembly of FIG. 1;

FIG. 3 is a left-side view of the capotasto and tuner assembly of FIG. 1;

FIG. 4 is a back view of the capotasto and tuner assembly of FIG. 1;

FIG. 5 is a front view of the capotasto and tuner assembly of FIG. 1;

FIG. 6 is a top view of the capotasto and tuner assembly of FIG. 1;

FIG. 7 is a bottom view of the capotasto and tuner assembly of FIG. 1;

FIG. 8 is an exploded perspective view of the capotasto and tuner assembly of FIG. 1 for ease of disclosure only; and, FIG. 9 is a perspective view of the capotasto and tuner assembly of FIG. 1 in use for ease of disclosure only.

The broken lines in FIG. 9 depict environment that forms no part of the claimed design.

The depicted capotasto and tuner assembly feature a unique appearance over the prior art. An electronic tuner is positionable on a jaw of the capotasto via cooperating attachment mechanisms on the tuner and capotasto jaw.

The nature and intended use of the article in which the design is embodied is a capotasto and tuner assembly for stringed musical instruments.
